(57) **CLAIM**

The ornamental design for a diffuser plate as shown and described.

DESCRIPTION

FIG. 1 is an isometric view of a diffuser plate.

FIG. 2 is a top plan view of the diffuser plate of FIG. 1.

FIG. 3 is a bottom plan view of the diffuser plate of FIG. 1.

FIG. 4 is a front elevation view of the diffuser plate of FIG. 1.

FIG. 5 is a rear elevation view of the diffuser plate of FIG. 1.

FIG. 6 is a left side elevation view of the diffuser plate of FIG. 1; and,

FIG. 7 is a right side elevation view of the diffuser plate of FIG. 1.

Portions of FIGS. 1 through 7 are shown in evenly spaced broken lines illustrating portions of the article that form no part of the claimed design. The dash-dot-dash broken lines in the drawings illustrate the boundary of the claimed design, which forms no part thereof.

1 Claim, 5 Drawing Sheets
